UNITED STATES PATENT OFFICE

GEORGE P. JACKSON, OF FLUSHING, NEW YORK, ASSIGNOR TO INTERNATIONAL COMBUSTION ENGINEERING CORPORATION, A CORPORATION OF DELAWARE

COAL DRIER

Application filed November 5, 1925. Serial No. 66,926.

This invention relates to coal driers such as are used in pulverized fuel preparing and handling plants, and it is especially useful where the heat for drying the coal is waste heat.

5 One of the difficulties encountered in waste heat driers is the ignition of the coal in the drier, this resulting, in most cases, from the fact that a quantity of coal will remain stagnant in the drier.

10 It is one of the principal objects of this invention to overcome this difficulty and secure more uniform movement and feed of the coal thru the drier.

15 How the foregoing, together with such other objects as may hereinafter appear, or are incident to my invention, are realized, is illustrated in preferred form in the accompanying drawings, wherein

20 Fig. 1 is a diagrammatic side elevation and partial section of the apparatus embodying my improvements, and

Fig. 2 is a diagrammatic view illustrating a modification of my improvements.

25 Referring now to Fig. 1 the reference character A indicates the pulverizing mill to which the coal, preferably crushed, is supplied from the bins 7 thru the intervening drier B.

30 The coal is fed from the bin 7 as by means of a star feeder 8, this feeder discharging preferably centrally of the drier casing 9.

To either side of the vertical center line of 35 this casing is mounted an endless chain or conveyor mechanism 10. This conveyor mechanism comprises endless belts or chains carrying shelves 11 preferably composed of angle iron. The chains pass over the drums 12, 12 and 13, 13, the drums 12 being preferably driven from the same shaft 14 which drives the star feeder. The conveyors move oppositely, that is to say, the adjacent flights move downwardly, these flights being spaced apart to provide a channel C between the two 40 conveyors, this channel being in line with the discharge spout 15 of the star feeder.

The coal discharged from the feeder enters 45 this passageway and by far the greater proportion of it lodges and remains on the shelves of the conveyors, whereby the coal is

fed downwardly to the bottom of the drier from whence it is discharged into the mill. Under normal operating conditions there will be no substantial accumulation of coal in the bottom of the drier and if for any reason there should be a tendency for an objectionable accumulation of coal at that point, the coal will be picked up by the upwardly moving flights of the conveyors for redischarge into the central passageway. It will thus be seen that stagnation in the drier is prevented and that the coal is more uniformly fed.

The heating medium of tempered or untempered flue gas is introduced into the heater thru the intake 16 which may be located at any desired point, the waste gases thereby admitted passing thru the column of coal being carried downwardly and eventually passing out of the drier thru the offtake 17. A fan in either the inlet or the offtake serves to produce the desired circulation. The amount of waste gases passed thru the drier is controlled by dampers 18.

If desired the coal may be somewhat agitated or tumbled from conveyor to conveyor, this being brought about by providing sinuous tracks 19 for the descending flights of the conveyors as indicated in Fig. 2.

What I claim is:

A coal drier comprising a casing having a coal inlet at the top and an outlet at the bottom, and two endless substantially vertically disposed conveyors spaced apart to provide a channel therebetween for the coal to be dried extending substantially from the inlet to the outlet, said conveyors being so operated that the adjacent flights thereof move in a direction from the inlet to the outlet and means for passing a heating medium through the casing and laterally through the descending fuel.

In testimony whereof, I have hereunto signed my name.

GEORGE P. JACKSON.
